TILTING CHAIR MOUNTING

Walter F. Herold, Bridgeport, Conn., assignor to
The Bassick Company, Bridgeport, Conn., a
corporation of Connecticut

Application June 15, 1939, Serial No. 279,318

16 Claims. (Cl. 155—77)

This invention relates to tilting chair mountings such as employed in office chairs, for example.

One of the objects of my invention is to provide a mounting that operates very quietly, and in which, nevertheless, the construction is very simple and inexpensive.

It is also a purpose of my invention to furnish a tilting mechanism requiring a minimum amount of lubrication for silent operation, and in which the tension of the resilient means is under effective and nice control, and in which also there are relatively few parts, which parts, moreover, are easy to assemble and easy of access when in the assembled position.

It is also aimed to provide a novel and improved resilient control device for tilting chairs, operating with a minimum of metal-to-metal contact.

To these and other ends the invention consists in the novel features and combinations of parts to be hereinafter described and claimed.

In the accompanying drawings:

Fig. 1 is a side elevation of a tilting chair mounting embodying my invention, the chair seat being shown in the normal or untilted position;

Fig. 2 is a top plan view of the tilting mechanism shown in Fig. 1, the chair seat being omitted;

Fig. 3 is a section on line 3—3 of Fig. 1;

Fig. 4 is a longitudinal section on line 4—4 of Fig. 2;

Fig. 5 is a section similar to Fig. 4 but illustrating the positions of the parts when the chair is tilted to a substantial degree;

Fig. 6 is a section on line 6—6 of Fig. 1;

Figs. 7 and 8 are views similar to Figs. 4 and 5, illustrating a modified form, and

Fig. 9 is a somewhat diagrammatic longitudinal sectional view of a further modified form of mounting.

In the drawings, a portion of the supporting base member of the chair is shown at 10, and a portion of the chair seat is shown at 11. The particular mounting shown for purposes of illustration is of the swivel type, and the screw-threaded spindle 12 screws up and down in the usual manner in the base 10, the vertical adjustment being accomplished by means such as a nut 13. The chair seat has on its under side the usual spider arms 14 fastened to the seat by screws 15. Extending across between the spider arms 14 and interconnecting them is a spanner member or spider horn 16, hereinafter more particularly described. This particular

chair mounting is of the low-fulcrum type, and the member 16 is fulcrumed at its lower part by means of a cross-pin or axle 17 to a body member 18, more particularly described hereinafter, said member 18 being rigidly fixed to the spindle 12, and constituting the fixed or stationary element of the pivotal (in this case hinged) joint between the spindle on the one hand and the spider arms on the other hand. This pivotal joint is under the control of a resilient control device comprising a bolt or tie rod member 19 having mounted thereon resilient members 20, as hereinafter more particularly described.

Referring now to the details of the mechanism, it will be noted that the fixed frame or body 18 is of composite construction, including an element 21 and an element 22. The element 21 is of U shape, and has in its lower connecting portion an opening 23 in which a portion of spindle 12, somewhat below the upper extremity of said spindle, is rigidly fixed in any appropriate manner. The member 22 is a smaller U-shaped member fitted within member 21 and riveted thereto by rivets 24, with the lower connecting portion 25 of member 22 spaced upwardly from the lower connecting portion of member 21. The upper extremity of spindle 12 is reduced and shouldered so as to provide a portion 26 headed over and tightly clenched in an opening 27 in the lower connecting portion of member 22. By this construction the composite element 18 comprising the parts 21 and 22 is very rigidly secured to the upper end of spindle 12 so as to be in fixed or stationary relation with respect thereto.

The spider horn or spanner 16, previously referred to, is of U shape so as to provide side walls 28, and a connecting rear wall 28a. At their upper portions the side walls 28 are rigidly fixed 40 to the spider arms 14, as by means of the rivets 29 and 30, of which two are employed in connection with each side wall or flange of the spanner member. Rivets 30 are offset upwardly to a certain extent from rivets 29. The hinge pin or 45 axle 17, previously referred to, passes through the walls 28 adjacent their front lower corners, and from these lower corners the walls 28 slope upwardly and rearwardly at their lower edges, as shown at 31. The hinge pin 17 passes through 50 the walls 28 and through the side walls of member 21, and for a considerable portion of its length it is located in the space between the lower portions of members 21 and 22, respectively.

The U-shaped member 22 is provided at its 55 forward portion with an integral extension 32

bent upwardly therefrom and forming a transverse wall closing in the space at the front of the pivotal joint structure. By so closing in this space a wall is created that is approximately opposite the wall 28^a, and a somewhat box-like structure is presented affording opposite relatively movable walls for the reaction of the resilient members 20, as hereinafter described.

For the purpose of providing a suitable stop mechanism to arrest the tilting movement at the proper points, I prefer to employ the rivets 29, previously mentioned, these rivets having protruding cylindrical heads 29^a at their inner ends, which heads are located within notches 33 formed in the upper ends of the side walls of member 21. At one end of the tilting movement each rivet 29 is at one end of the notch in contact with a portion 34 of member 21, and at the other end of the movement the rivet is in contact with a portion 35 at the other end of the notch.

The resilient members 20, previously mentioned, mounted on the bolt or rod 19, are arranged respectively in front and at the rear of the box-like joint structure, previously described, with one of said resilient members located adjacent wall 28^a to act thereon, and the other similarly located adjacent wall 32. The bolt 19 is approximately horizontally arranged. The resilient members 20 may be formed as rubber blocks or as springs, but in the particular example illustrated, they are shown as comprising cylindrical resilient rubber sleeves having central openings or bores 20^a through which the bolt 19 passes for tying together and controlling the operation of the resilient counterbalancing elements. In the example shown, the bolt 19 is provided at its rear extremity with a rounded head 36 having at the under side thereof a square portion 37 adapted to fit a square hole 38 in a washer 39 held in place by head 36 against a retainer 40 in the form of a shallow metal cup encircling and receiving one end of the adjacent rubber cylinder 20. The square portion 37 engages a square hole 41 in this retainer, and it will be understood that by the construction described neither the washer 39 nor the retainer 40 can turn relatively to the body of the bolt 19. At the opposite end of the same rubber block 20 is arranged a similar retainer 42, and this retainer is abutted against the outer face of wall 28^a, and is held in fixed relation thereto by means such as rivets 43. The bolt 19 passes through the wall 28^a and member 42, for which purpose wall 28^a is provided with a clearance slot 28^b, and member 42 with a clearance slot 42^a, these slots being of such a size that there is no interference with the swinging movement of the bolt 19 hereinafter referred to. The resilient member 20 at the front of the pivot joint structure is mounted similarly to the rear resilient member, having rear and front retainers 44 and 45 of shallow cup shape similar to retainers 40 and 42. The bolt 19 passes through wall 32 of the fixed joint member in a notch 46 formed in wall 32, and retainer 44, which is riveted to wall 32 by rivets 47, has a clearance slot 48 adjacent notch 46. Retainer 45 has a round hole 49 in which the threaded portion 50 of bolt or tie rod 19 is located, and in front of retainer 45 a washer 51 is placed around the threaded portion 50. Engaging the threaded portion 50 of the bolt are interior threads 52 in a shank 53 of a nut member 54 having a head 55 of convenient shape for turning by the hand. It will be understood that by screwing up on the nut 54, which is conveniently located be-

neath the chair seat forwardly of the fulcrum point, the resilient elements can be subjected to compression, in an obvious manner, and the degree of this compression nicely regulated.

5 The normal position of the parts when the chair is unoccupied is shown in Fig. 1. As customary, the chair seat 11 has a small amount, say three degrees, of initial tilt. The hand-adjusting nut 54 will be screwed up on bolt 19 to compress the rubber sleeves 20 to the required degree to provide the desired resistance to the tilting movement of the chair seat when the latter is occupied. When the chair is in the un-tilted or normal position the stops 29 are in contact with the portions 34. When the chair seat is occupied and the same tilted rearwardly, as shown in Fig. 5, the movable member 28^a is swung rearwardly so as to exert compressive force on the rear resilient member 20 from the front of said member, moving said member rearwardly, and as the rear portion of said member is moved in a rearward direction, the bolt 19 is pulled in a rearward direction. The result of this rearward pull on the bolt is to carry nut 54, washer 51, and retainer 45 in a rearward direction, thereby exerting compressive force on the front member 20 from the front thereof, so as to exert compressive force on said member 20 between its retainers 45 and 44. Thus it will be understood that the member 19 ties the two resilient elements together, so that compression exerted upon one will be transmitted to the other through the endwise moving tie rod.

These compressive effects upon the rubber sleeves or blocks are, in a general sense, axially directed, inasmuch as the rubber sleeves are approximately horizontally aligned for tying together in a substantially horizontal direction by their connecting or tying member, but it will be understood that in moving from the position shown in Fig. 4 to the position shown in Fig. 5, for example, a certain relative displacement of the respective members 20 occurs, and that the member 19 is also relatively displaced. Such movements cause a certain amount of twisting and distortion of the rubber sleeves, as well as longitudinal compression, and this is indicated to an extent in Fig. 5.

It will be noted that the bores or holes in the rubber sleeves are of appreciably larger diameter than the bolt 19, and that in the tilting of the chair seat the tie member or bolt will float freely in swinging and translatory movement without contacting the members of the pivot joint. The only contacts of bolt 19 with metal are those which the bolt has with the retaining or head structures at the rear face of the rear rubber sleeve, and at the front face of the front rubber sleeve, and it is to be borne in mind that these retainer or head structures are supported in a cushioned and therefore silently working manner by the rubber sleeves. The only part of the mechanism which may require lubrication (at rather long intervals) is the fulcrum connection provided by the pin 17 or its equivalent. It is not necessary to lubricate the resilient counterbalancing means having the free-floating connecting member on account of the entire absence of metal-to-metal contacts capable of creating squeaks or other noises.

In Figs. 7 and 8 is shown a form which is the same as that above described except for the means for positioning the inner portions of the rubbers 20. In this case, instead of using shallow retainers such as 42 and 44, I employ the members 42^a and 44^a. These, as before, are fixed to

and carried by the walls 28^a and 32 respectively, but they are constituted by deeper cup-like members surrounding a greater portion of the periphery of the rubber sleeve. Moreover, these cups are of outwardly sloping or flaring shape and so arranged that initially the rubber members contact substantially their bottoms only, as shown in Fig. 7, there being a tapered space between the periphery of each sleeve and the surrounding cupped or bell-shaped member. However, when the chair is tilted, the action is as shown in Fig. 8, the rubber being forced out into the tapered or wedge-shaped space, particularly at the upper part of the rubber sleeve, and only a portion (in this instance slightly more than one-half of the length) of the rubber mass being free to expand or bulge beyond the mouth of the cup. In this manner the action of the rubber body is very effectively controlled for the purposes in view. One of the principal advantages of this sloping or conical cup wall formation is that there is greater control of the compression, and another advantage arises from the centering effect of the cup, which tends to center and hold the rubber body in proper position with respect to the inner member of the pivotal structure with which it reacts to produce the counterbalancing effect.

In practice I deem it preferable to give the mouth or rim portion of the cup a slight outward curve, as indicated at 42^b and 44^b.

In Fig. 9 I have shown in a somewhat diagrammatic manner a modified form of my tilting mounting in which the chair has a so-called high fulcrum. In this case the fixed or stationary member of the pivot joint is shown at 56, and this member is pivoted at 57 (approximately at the same elevation as the spider arms 58) to a swinging member 59 rigid with the spider arms having a front wall 60 against which front resilient member 61 is positioned. Rear resilient member 62 is positioned adjacent a fixed wall 63 rigid with the stationary member 56. Spindle 64 passes through a slot 65 in wall 60 and through a slot 66 in wall 63. When the chair is tilted backwardly, wall 63 is swung forwardly to compress front rubber member 61, and through the pull on the spindle 64 the rear rubber member 62 is compressed by pressure exerted on its rear portion. It will be noted that in this instance also the pivot joint adapted to connect the chair seat to the supporting post is characterized by a generally box-like structure presenting at one end a transverse forwardly and rearwardly swinging wall, and at the opposite end a transverse fixed wall, these walls being resiliently tied together by a device including a resilient member located behind and acting against the rear wall, and a resilient member located in front of and acting against the front wall, said resilient members being mounted tandemwise on a common spindle or tie rod passing through the front and rear walls of the joint structure and arranged to transmit compressive action from one resilient member to the other so that they are caused to operate simultaneously. In this manner a very strong and durable structure is provided which is not likely to get out of order, and which is provided with ample counterbalancing means for the chair, which means is under a nice control. I have already referred to the noiselessness of the operation, and it will be apparent that the construction is such that the parts are relatively few in number and of simple structure, and capable of ready assemblage and disassemblage.

The compression rubbers are especially desirable on account of their simple character and noiseless operation, and also on account of their long service. However, as indicated above, coiled springs can be substituted if desired.

In one aspect of my invention the wall members above referred to, against which the rubber members are positioned, one in front of one wall member and the other at the rear of the other wall member, may be considered as interpivoted leaves spaced apart in a forward and rearward direction, and under the control of a resiliently acting device which ties them together, said device comprising a tie rod passing through clearance openings in said leaves and having a portion disposed in the space between the leaves, such tie rod with its accessories providing a connecting means between the resilient members whereby on backward tilt of the chair seat both of said resilient members are compressed, in which operation the tie rod proper is subjected to tension.

It will be understood that I have illustrated only three forms which my invention may assume, and that it is capable of many and various embodiments and modifications and changes in the detail structure without departure from the principles involved or from the scope of the appended claims.

What I claim is:

1. In a tilting chair mounting, a pair of spider arms, a spanner comprising a U-shaped member having side walls attached to the respective spider arms, the attachment being effected at least in part by rivets having inwardly disposed heads, a relatively fixed member to which said spanner has pivotal relation adjacent the lower end of the spanner, said fixed member having side walls with notches at the upper parts thereof in which the protruding heads of said rivets operate in order to act as stops, and resilient means resisting tilting of the spanner and spider arms.

2. In a tilting chair mounting, rubber cylinders substantially in axial alignment, a two-part pivotal structure between the cylinders, a tie member passing through the pivotal structure and through bores of the cylinders, and retainers for the inner ends of the cylinders carried by the respective parts of the pivotal structure.

3. In a tilting chair mounting, rubber cylinders substantially in axial alignment, a two-part pivotal structure between the cylinders, a tie member passing through the pivotal structure and through bores of the cylinders, and retainers for the inner ends of the cylinders carried by the respective parts of the pivotal structure, said retainers being relatively deep cups having substantially conical walls.

4. In a tilting chair mounting, two relatively swingable members, one adapted for securement to a chair seat and the other for securement to a supporting post, said members having leaf portions arranged one in front of the other, and a cushioning and tensioning device arranged to confine the leaf portions from the outside for resisting tilting, said device comprising a floating tie rod extending between and beyond said leaf portions, and rubber cylinders held on said tie rod one in front of the front leaf portion and the other at the rear of the other leaf portion, said cylinders mounting said rod for swinging and endwise movements.

5. In a chair iron structure, a post-supported frame, a chair-seat-attached spanner member hinged to said frame for tilting movement about

a horizontal axis, said spanner member having a clearance opening therein and said frame having a part spaced somewhat forwardly of that part of the spanner member having the clearance opening and itself provided with a clearance opening in a portion of said frame acting as a resilient element supporting head, a rod passing freely through said clearance openings and having a substantial portion of its length disposed at the outer or remote side of said head, a resilient element disposed about and held on said rod at the last-named portion thereof, said rod extending at the other end beyond the clearance opening portion of the spanner member, and means for swingingly mounting the last-named end of the rod relatively to the spanner member comprising a rubber member mounted on the rod, and inner and outer retainers for said rubber member surrounding the rod.

6. In a tilting chair mounting, rubber cylinders substantially in axial alignment, a two-part pivotal structure between the cylinders, a tie member passing through the pivotal structure and through bores of the cylinders, retainers for the inner ends of the cylinders carried by the respective parts of the pivotal structure, and retainers for the outer ends of the cylinders carried by the tie member.

7. In a chair iron structure, a post-connected frame having a substantially upright part, a chair-seat-supporting spanner member hinged to said frame for tilting movement and having a substantially upright part facing that of the frame, a substantially horizontal rod passing with clearance through said substantially upright parts and having end portions extending beyond them, resilient seat-cushioning members surrounding said end portions, and elements on the end portions of the rod holding the respective resilient members in position against the respective members of the frame-spanner structure with the rod under tension and tiltably and resiliently held at one end from the spanner member for free swinging and translating movements, the rearward tilting of the chair seat causing a pull on the rod through the resilient member adjacent the spanner which pull acts to compress the other resilient member.

8. A chair iron structure such as set forth in claim 7 in which the resilient member adjacent the spanner member is a rubber cylinder, and in which the spanner member carries a cup-shaped retainer for said cylinder.

9. A chair iron structure such as set forth in claim 7 in which both resilient members are constituted by rubber cylinders, the frame having a cup-shaped retainer receiving one end of one cylinder and the spanner member having a cup-shaped retainer receiving a portion of the other cylinder.

10. In a chair iron structure, a frame, a chair-seat-supporting spanner member having a substantially forwardly and rearwardly facing leaf portion with a clearance opening, said frame and spanner member hinged together for tilting movement of said spanner member, a substantially horizontal rod extending through said clearance opening and through a facing rod-clearing portion of the frame and having end portions located respectively beyond the frame and spanner member, resilient seat-cushioning members disposed around said end portions, and elements on the end portions of the rod holding the respective resilient members in position against the respective members of the frame-

spanner structure with the rod under tension and tiltably and resiliently held at one end from the spanner member for free swinging and translating movements.

5 11. In a tilting chair mounting, axially compressible rubber cylinders in substantially horizontal axial alignment and spaced apart, a pivotal structure between the cylinders having parts attached respectively to a chair seat and to a base and pivoting on an axis substantially transverse to the cylinders, and a tie member passing through the pivotal structure and through bores of the cylinders and tensioned by the cylinders and serving to maintain compression of the cylinders, said pivotal structure having its chair-seat-attached part movable in a generally rearward direction to increase the tension and being reversely movable to decrease the tension.

6 12. In a tilting chair mounting, chair-seat-attached spider arms, a spanner of substantially U shape set in between said spider arms and having an open top and a rearwardly disposed transverse wall, a composite frame member comprising interconnected upper and lower U-shaped elements arranged in the space between the side walls of said spanner and pivoted to said spanner, said composite member including a transverse substantially upright wall on one of said elements spaced forwardly from and facing said first-named transverse wall, and a cushioning and tensioning device for the chair seat arranged to confine said transverse walls from the outside for resisting tilting of the chair seat, said device comprising a floating tie rod extending between 13 and beyond said transverse walls, and elastic rubber cylinders on said tie rod one in front of one of said walls and the other at the rear of the other wall, said cylinders mounting said rod for swinging and endwise movements.

14 13. In a tilting chair mounting, a screw-post-attached frame member having an upwardly projecting leaf portion, a chair-seat-attached spanner member hinged to said frame member for tilting movement and having an upwardly directed leaf portion behind and facing said first leaf portion, a tie rod passing in a forward and rearward direction through clearance openings in the respective leaf portions, said tie rod being continued forwardly substantially beyond the first leaf portion, an elastic rubber compression member surrounding the rod in front of the first leaf portion, means on the front end portion of the rod between which and the first leaf portion said rubber member is adapted to be regulably compressed, means at the rear of the spanner for mounting from the spanner the other end portion of the rod, said rod being mounted for free swinging and translating movements and being adapted on rearward movement of the spanner to increase the compression of said rubber member, and means associated with said first-named leaf portion for controlling the lateral expansion of a portion of said rubber member.

15 14. In a tilting chair mounting, a screw-post-attached frame member having an upwardly projecting leaf portion, a chair-seat-attached spanner member hinged to said frame member for tilting movement and having an upwardly directed leaf portion behind and facing said first leaf portion, a tie rod passing in a forward and rearward direction through clearance openings in the respective leaf portions, said tie rod being continued forwardly substantially beyond the first leaf portion, an elastic rubber compression

member surrounding the rod in front of the first leaf portion, means on the front end portion of the rod between which and the first leaf portion said rubber member is adapted to be regulably compressed, means at the rear of the spanner for mounting from the spanner the other end portion of the rod, said rod being mounted for free swinging and translating movements and being adapted on rearward movement of the spanner to increase the compression of said rubber member, and members surrounding the tie rod adjacent the front and rear ends of the rubber member which restrict the expansion of said rubber member at the front and rear.

15. In a tilting chair mounting, a screw-post- attached frame member having an upwardly projecting leaf portion, a chair-seat-attached spanner member hinged to said frame member for tilting movement and having an upwardly directed leaf portion behind and facing said first leaf portion, a tie rod passing in a forward and rearward direction through clearance openings in the respective leaf portions, said tie rod being continued forwardly substantially beyond the first leaf portion, an elastic rubber compression member surrounding the rod in front of the first leaf portion, means on the front end portion of the rod between which and the first leaf portion said rubber member is adapted to be regulably compressed, means at the rear of the spanner for mounting from the spanner the other end portion of the rod, said rod being mounted for free swinging and translating movements and being adapted on rearward movement of the spanner to increase the compression of said rubber member, and members surrounding the tie rod adjacent the front and rear ends of the rub-

ber member which restrict the expansion of said rubber member at the front and rear, the rubber member being confined to a greater extent at the rear end than at the front end.

16. In a tilting chair mounting, a screw-post- attached frame member having an upwardly projecting leaf portion, a chair-seat-attached spanner member hinged to said frame member for tilting movement and having an upwardly directed leaf portion behind and facing said first leaf portion, a tie rod passing in a forward and rearward direction through clearance openings in the respective leaf portions, said tie rod being continued forwardly substantially beyond the first leaf portion, an elastic rubber compression member surrounding the rod in front of the first leaf portion, means on the front end portion of the rod between which and the first leaf portion said rubber member is adapted to be regulably compressed, means at the rear of the spanner for mounting from the spanner the other end portion of the rod, said rod being mounted for free swinging and translating movements and being adapted on rearward movement of the spanner to increase the compression of said rubber member, and members surrounding the tie rod adjacent the front and rear ends of the rubber member which restrict the expansion of said rubber member at the front and rear, the rubber member being confined to a greater extent at the rear end than at the front end, and the restricting member at the rear end of the rubber member being constituted by a flange projecting forwardly from the adjacent leaf portion and having an outwardly flared rim.

WALTER F. HEROLD.
